YARN TUBE UNIT FOR AXMINSTER TUBE FRAMES

Walter Y. Robb, Whitinsville, Mass., assignor to Crompton & Knowles Loom Works, Worcester, Mass., a corporation of Massachusetts

Continuation of application Serial No. 785,988, November 14, 1947. This application September 30, 1950, Serial No. 187,815

6 Claims. (Cl. 139—10)

1

This is a continuation of application Serial No. 785,988, filed November 14, 1947, now abandoned.

This invention relates to Axminster looms and it is the general object of the invention to provide an improved yarn tube unit for the tube frames of Axminster looms.

Axminster looms operate with a large number of tube frames each of which carries spools wound with variously colored tuft forming yarns. These yarns extend downwardly from the spools through spaced tubes secured to the tube frame. During a tuft forming operation the tube frame is dipped so that the yarn tubes and the yarns projecting from them extend below the warp sheds.

Yarn tubes as heretofore constructed have caused difficulty in the manipulation of the tuft yarns due partly to the manner in which the yarn tubes are made and also the manner in which they are attached to the tube frame. One common method of making a tube frame is to provide a series of yarn tubes independent of each other and held on a sheet steel bracket or the like extending along the metal tube of the tube frame. Such yarn tubes do not always preserve their correct alignment because of their individual mountings and it is necessary to bend them from time to time so that they will register with the binder warps during the tube frame dipping operation. Furthermore, the yarn tubes have ordinarily been made from sheet metal folded on itself in such manner that the overlapping edges catch on the tuft yarns.

It is an important object of the present invention to provide a comparatively short yarn tube unit provided with a plurality of yarn tubes formed integral with a body or base member adapted for attachment to the bar of the tube frame, and so constructed that the yarn passages formed interiorly of the yarn tubes will be smooth and offer no appreciable resistance to movement of yarns through them.

It is another object of the invention to provide the unit with a rail, shelf or the like extending laterally from the base or body and having integral therewith a set of yarn tubes the thread passages of which open upwardly through the rail.

It is a still further object of the invention to provide a unit made of a moldable or plastic material, such as a die casting or a plastic resin, wherein all parts of the unit are integrated with each other. Units made in this way are accurately dimensioned and can be secured to the tube frame side by side with the yarn tubes properly spaced along the length of the tube frame.

2

With these and other objects in view which will appear as the description proceeds, my invention resides in the combination and arrangement of parts hereinafter described and set forth.

5 In the accompanying drawings, wherein a convenient embodiment of the invention is set forth,

Fig. 1 is an elevation of one end of a tube frame showing a clutch for releasing the tube frame from one of the transporting chains.

10 Figs. 2 and 3 are vertical sections on lines 2—2 and 3—3, respectively, of Fig. 1.

Fig. 4 is an enlarged vertical section on line 4—4 of Fig. 3, and.

15 Fig. 5 is a plan view looking in the direction of arrow 5, Fig. 4, the base or body of the unit being shown in section.

Referring particularly to Fig. 1, the tube frame designated generally at T comprises an elongated tubular bar 10 which may be of rectangular cross section. A bracket 11 is secured to the end of the bar and has a spool bearing 12 for one end of the yarn spool 13. The latter will ordinarily be wound with a number of differently colored yarns used in the formation of the tufts of Axminster fabrics. In order to clarify the showing of Fig. 1 only one of these yarns is shown at Y.

The bracket 11 also has a tongue 15 which extends between the links of a transporting chain designated at 16, and a hook 17 overhangs one of the links of the transporting chain and is the means by which the tube frame is supported on the chain.

30 The loom is provided with a clutch 18 having a foot 19 and side wings one of which is shown at 20. The upper part 21 of the clutch is adapted for engagement with the hook 17. When a tube frame reaches the transfer station in the loom the clutch 18 will move inwardly, and after the foot 19 has passed under the bar 10 the hook 17 will be moved to the left as viewed in Fig. 1 to disconnect the tube frame from the chain 16. The clutch then descends to dip the tube frame and enable it to perform the tuft forming operation. During the latter part of the operation the tube frame is raised and the spool 13 turns as enough yarn is drawn off for the next row of tufts which the tube frame will form when it is active again. A brake 22 for the spool prevents excess angular movement of the latter during 40 pulling-off operation.

The matter thus far described is usual in the construction of Axminster tube frames and of itself forms no part of my present invention except as indicated hereinafter.

45 55 The tuft forming yarn Y must be guided and also held in spaced relation during the tuft forming operation. This result is usually accom-

plished by means of yarn tubes already mentioned herein, but such tubes as heretofore made have had rough edges in their yarn guiding passageways, and furthermore they have ordinarily been separate from each other and individually held to the tube frame in such manner as has permitted them to lose their alignment.

In carrying my present invention into effect I provide a tuft yarn tube unit designated generally at U comprising a base or body 30 which is flat and is held against the adjacent side wall 31 of the bar 10 by means of screws 32. The latter are tapped into the wall 31 as indicated in Fig. 3, but I do not wish necessarily to be limited to this particular means of attaching the body 30 to the bar.

Extending laterally from the body 30 is a flat rail, shelf or the like 35 which when the unit is in position on the tube frame will be parallel to the latter as indicated for instance in Fig. 2. Depending from the rail are yarn tubes 36 which are spaced from each other as indicated in Fig. 1 and provided with smooth interior yarn guiding passages 37. These passages extend entirely through the yarn tube 36 and communicate with and open upwardly through mouths 38 formed in rail 35, as indicated in Figs. 3 and 4.

Extending upwardly from the rail 35 in a direction more or less parallel to the body 30 is a stiffening wall 40 connected to body 30 by several thin reinforcing fins 41. These fins are of a thickness which does not exceed the space between adjacent passages 37 and therefore do not interfere with yarns Y as the latter pass from the spool to the passages.

In order that the unit may be correctly positioned on the bar 10 the base 30 may be formed with a lateral flange 45 which overhangs the top 46 of the bar 10 as viewed in Fig. 3. While flange 45 is a convenient means for locating the unit U on the tube frame I do not wish necessarily to be limited to it in the practice of the invention.

A significant feature of the invention is that all parts of the unit are integral with each other and the yarn tubes have continuous and uninterrupted smooth yarn passages through them, a feature which so far as I am aware has not previously been attained in the manufacture of tube frames. The material of which the unit is made may conveniently be a linear polyacamide thermoplastic, or more briefly a polyamide resin, this material being marketed under the trade name nylon. Such a material is strong and will hold its shape, is not subject to the rusting which is such a common fault with metal yarn tubes heretofore used, and is transparent so that the condition of the tuft yarns Y in the tubes 36 can be determined visually.

The yarn tube unit can be made not only of the polyamide resin already mentioned, but can also be made of other plastics, such as vinyl chloride, phenolic formaldehyde, or methyl methacrylate, and if desired can be formed as a metallic die casting.

From the foregoing it will be seen that I have provided a simple compact yarn tube unit for an Axminster tube frame wherein the supporting base or body 30 which is attached to the tube frame has formed integrally therewith the yarn tubes and the rail 35 from which the tubes depend. It will also be seen that the rail 35 is reinforced both by the wall 40 and the fins 41. The interior passages 37 for the tuft yarns are smooth to permit uninterrupted movement of the yarns through them. The yarn passages open

5 through the rail 35 and their peripheries transverse of the length of the tubes are uninterrupted. The preferred form of the invention is made of a transparent plastic material, preferably a polyamide resin, permitting the yarns to be seen through the tubes.

Having thus described the invention it will be seen that changes and modifications of the foregoing specific disclosure may be made without departing from the spirit and scope of the invention.

What is claimed as new is:

1. A yarn tube unit for an Axminster tube frame, said unit comprising a body adapted for attachment to the tube frame, a rail projecting laterally from the body, a wall extending from the rail, reinforcing fins transverse of the body connecting the latter to said wall, and a plurality of parallel spaced yarn tubes projecting from said rail and each formed with a yarn passage opening through said rail, said fins having a thickness not substantially exceeding the distance between adjacent yarn passages and being located along said unit at intervals corresponding to groups of yarn passages and defining a space for each group between said body and wall communicating with the yarn passages of the group.

2. A yarn tube unit for an Axminster tube frame including a longitudinal bar, said unit comprising a body adapted for attachment to said bar, a rail extending laterally from said body and having yarn receiving mouths formed therein, and a plurality of parallel yarn tubes continuous in transverse section supported by and projecting laterally from the rail and having tuft yarn receiving passages therethrough communicating with and opening through said mouths in the rail, the latter and the mouths therein lying in a plane perpendicular to said yarn passages.

3. A yarn tube unit for an Axminster tube frame, said unit comprising a body adapted for attachment to the tube frame, a rail projecting laterally from the body, a wall spaced from said body and extending from the rail in a given direction, reinforcing fins transverse of the body connecting the latter to said wall, and a plurality of parallel spaced yarn tubes projecting from said rail in a direction opposite to said given direction and each formed with a yarn passage opening through said rail between said body and that part of said wall adjacent to said rail, said body, rail, wall, fins and yarn tubes all being integral with each other, said fins being spaced along the unit at intervals corresponding to a plurality of 50 yarn passages to define spaces between the rail, body and wall into which said yarn passages open.

4. A yarn tube unit for an Axminster tube frame including a longitudinal bar, said unit comprising a flat body adapted for attachment to said bar, a rail extending laterally from said body and having yarn receiving mouths formed therein, a plurality of parallel yarn tubes continuous in transverse section supported by and projecting laterally from the rail and having tuft yarn receiving passages therethrough communicating with and opening through said mouths in the rail, and flat reinforcing fins parallel to said passages connecting the rail to the body, said rail and the mouths therein lying in a plane perpendicular to said yarn passages.

5. The yarn unit set forth in claim 4 wherein the fins are located between said mouths in the rail.

6. A yarn tube unit for an Axminster tube frame including a longitudinal bar, said unit com-

prising a flat body adapted for attachment to said bar, a plurality of parallel yarn tubes integral with said body continuous in transverse section extending from said unit and having tuft yarn receiving passages therethrough, said tubes having parts thereof formed as extensions of the body so that continuations of said passages lie along said body.
